United States Patent Office

Des. 188,256

Patented June 21, 1960

188,256

PORTABLE DRIER

Robert M. Hayes, 6 Sidney St., Watertown, Mass.

Filed June 15, 1959, Ser. No. 56,344

Term of patent 14 years

(Cl. D49—1)

Fig. 1.

Fig. 2.

Fig. 1 is an isometric view of the portable drier in collapsed condition; and

Fig. 2 is an isometric view of said drier in opened-out condition.

The hidden side is substantially the same as the side shown. Other surfaces unseen in the figures are substantially plain.

I claim:

The ornamental design for a portable drier, substantially as shown and described.
